BIRD FEEDER OR THE LIKE

Samuel E. Clegg, 729 Bartlett Ave., Plainfield, Ill.

Filed Oct. 7, 1960, Ser. No. 62,424

Term of patent 14 years

(CL. D31—2)

FIG. 1 is a top plan view of a bird feeder showing my new design;

FIG. 2 is a vertical sectional view thereof taken on the line 2—2 of FIG. 1;

FIG. 3 is a bottom plan view thereof;

FIG. 4 is a bottom perspective view thereof on a reduced scale;

FIG. 5 is a top perspective view thereof on a reduced scale; and

FIG. 6 is a top perspective view of a modified form thereof on a reduced scale, the bottom side being substantially the same as shown in FIG. 3.

I claim:

The ornamental design for a bird feeder or the like, substantially as shown and described.
